TRAIN CONTROL APPARATUS

Clyde C. Farmer, Pittsburgh, and Thomas H. Thomas, Edgewood, Pa., assignors to The Westinghouse Air Brake Company, Wilmerding, Pa., a corporation of Pennsylvania

Application February 15, 1924, Serial No. 692,970
Renewed November 3, 1926

53 Claims. (Cl. 303—18)

This invention relates to an automatic train speed control equipment adapted to control the speed of the train in accordance with the signal indication.

5 Although a train may be equipped with an automatic speed control apparatus for automatically controlling the speed in accordance with the signal indication, it is considered desirable to ensure that the engineer is attending to his duties at all 10 times and it is therefore desirable to compel the engineer, under penalty, to keep the speed of the train within the speed limit required by the signal indication, by his own acts.

Accordingly, one feature of our invention consists in providing a train speed control equipment, in which, when the signal indication changes from a more favorable to a less favorable condition, the engineer will be required, under penalty, to make an application of the brakes 20 sufficient to bring the speed of the train down to or below the speed limit as indicated by the signal indication and furthermore, he must also acknowledge the signal indication, under certain conditions, even if the speed of the train in passing a signal indication is below the speed limit required by the signal indication.

It is well known that a train, particularly a long train, can be handled more smoothly by making a graduated rather than a continuous 30 application of the brakes, since when a heavy, continuous reduction in brake pipe pressure is effected, there is danger that the brakes will be applied at the head end of the train before they are applied at the rear end, and with such force 35 as to cause the slack of the train to run in harshly and thus cause dangerous shocks.

To prevent this, it has been the practice to first make a light reduction in brake pipe pressure, and then, after moving the brake valve handle 40 to lap position and holding the same there until the brake pipe exhaust ceases, to effect a further heavier reduction in brake pipe pressure. This method of applying the brakes is known as a split reduction or two application stop.

45 The same condition would obtain where the reduction in brake pipe pressure to effect an application of the brakes is made by the operation of an automatic train control equipment and therefore another feature of our invention consists in providing means associated with an automatic train control equipment for automatically effecting a two stage reduction in brake pipe pressure when the train control apparatus 50 operates to effect an application of the brakes.

55 Another feature of our invention is to provide

means for cutting the two stage brake pipe reduction feature out of action under certain conditions.

Another object of our invention is to provide means for ensuring that when the engineer manipulates the brake valve to effect a reduction in 5 brake pipe pressure, he must make a predetermined reduction in brake pipe pressure, or the train control apparatus will act.

Another object is to provide means for preventing the train control apparatus from acting, if the engineer makes a predetermined reduction in brake pipe pressure within a predetermined period of time.

Another object is to provide means for preventing failure to function properly due to possible leakage past the equalizing discharge valve when said valve is in its closed position.

Another object is to provide means for permitting the use of fluid in the train control apparatus at a predetermined pressure less than the main reservoir pressure, while at the same time providing for the use of main reservoir pressure at the brake valve, in order to avoid the deposit and condensation of moisture in the train control 20 apparatus.

Another object is to provide an improved brake valve device for use in connection with a train control equipment.

Another object is to generally simplify the 30 train control apparatus and to reduce the number of working parts to a minimum.

Other objects and advantages will be apparent in the following more detailed description of the invention.

In the accompanying drawings; Fig. 1 is a diagrammatic view, partly in section, of an automatic train speed control equipment embodying our improvements; Fig. 2 a central sectional view of the brake application valve unit of the train control equipment; Fig. 3 a diagram illustrating the operation when a medium speed signal indication is received; and Fig. 4 a diagram illustrating the operation when a low speed signal indication is received.

45 In general, the train control equipment may comprise a governor valve unit, a brake application valve unit, a brake valve device 1, and an acknowledging valve device 2.

The governor valve unit may comprise a centrifugal governor portion 3, a change speed valve portion 4, a timing portion 5, and a magnet and pipe bracket portion 6. The governor portion 3 comprises a rotatable member 7 having a pinion 8 meshing with a pinion 9, the pinion 9 being 50 55

operatively connected with a locomotive axle so as to rotate at a speed which varies according to the speed of the train. The member 7 carries governor balls 10 adapted to operate a spindle 11 in accordance with the speed of the train. A cross head 12 is carried by the spindle 11 and is adapted to operate a series of governor valves 13, 14, and 15, and blow down timing valves 16 and 17.

10 The change speed valve portion 4 comprises a casing containing a high speed valve device, a medium speed valve device, and an acknowledging pilot valve device.

The high speed valve device comprises a piston 18 contained in piston chamber 19 and a slide valve 20 contained in valve chamber 21 and adapted to be operated by piston 18. The medium speed valve device comprises a piston 22 contained in piston chamber 23 and a slide valve 24 contained in valve chamber 25 and adapted to be operated by piston 22. The acknowledging pilot valve device may comprise a piston 26 contained in piston chamber 26^a, a valve piston 27 contained in valve chamber 28, and a valve 29 contained in valve chamber 30, said valve piston 27 and the valve 29 being operable by piston 26.

15 The timing portion 5 comprises a casing containing a high to medium speed timing valve device and a medium to low speed timing valve device. The high to medium speed timing valve device comprises a flexible diaphragm 31 subject on one side to the pressure in diaphragm chamber 32 and on the opposite side to the pressure of a coil spring 33, and a double beat valve 34, contained in valve chamber 35 and operable by the diaphragm 31. The medium to low speed timing valve device comprises a flexible diaphragm 36, subject on one side to the pressure in a diaphragm chamber 37 and on the opposite 20 side to the pressure of a coil spring 38, a valve 39 contained in spring and valve chamber 40, and a valve 41 contained in valve chamber 42, said valves being operable by the diaphragm 36.

25 The magnet and pipe bracket portion 6 comprises a casing to which all the controlling pipes of the governor unit are connected and containing a high speed magnet valve device and a medium speed magnet valve device. The high speed magnet valve device comprises a magnet 43 and valves 44 and 45 operable by said magnet. The medium speed magnet valve device comprises a magnet 46 and valves 47 and 48 operable by the magnet 46.

30 The brake application valve unit comprises a pipe bracket portion 49, a brake pipe reduction ensuring and brake application suppressing portion 50, a brake application portion 51, a split reduction cut-out portion 52, and an equalizing discharge valve portion 53.

35 The pipe bracket portion 49 comprises a casing to which all of controlling pipes of the brake application valve unit are connected and containing a first reduction reservoir 54, a second reduction reservoir 55, and timing reservoir No. 1, and a timing reservoir No. 2.

40 The brake pipe reduction ensuring and brake application suppressing portion 50 comprise a casing containing a brake pipe reduction ensuring valve device and a brake application suppressing valve device. The brake pipe reduction ensuring valve device may comprise a flexible diaphragm 56 subject to the opposing fluid pressures in diaphragm chambers 57 and 58, and adapted to operate valves 59 and 60 contained in valve chamber 61. The brake application sup-

55 pressing valve device may comprise a flexible diaphragm 62, subject on one side to the pressure in diaphragm chamber 63 and adapted to operate valves 64 and 65 contained in valve chamber 66.

5 The brake application portion 51 comprises a casing containing a brake application valve device, a pilot piston valve device, a reduction timing valve device, and a reduction hold back valve device. The brake application valve device may 10 comprise a piston 67 contained in piston chamber 68, and a slide valve 69, contained in valve chamber 70 and adapted to be operated by piston 67. The pilot piston valve device may comprise a piston 71, contained in piston chamber 72 and 15 a slide valve 73, contained in valve chamber 74, and adapted to be operated by piston 71.

20 The reduction timing valve device may comprise a piston 75 subject on one side to the pressure in piston chamber 76 and a valve 77, contained in the valve and piston chamber 78 and adapted to be operated by piston 75. The reduction hold back valve device may comprise a piston 79, subject on one side to the pressure in piston chamber 80, and a valve 81, contained in 25 valve chamber 82 and adapted to be operated by piston 79.

25 The split reduction cut-out portion 52 contains a piston 83, contained in piston chamber 84, and a slide valve 85, contained in valve chamber 86 and adapted to be operated by piston 83.

30 The equalizing discharge valve portion 53 contains an equalizing discharge valve mechanism comprising a piston 87 having a chamber 88 at one side connected through pipe and passage 35 89 to an equalizing reservoir 90, and a valve 91 contained in chamber 92 at the opposite side of the piston and adapted to be operated by said piston.

35 The portion 53 also contains a reduction safety 40 valve device comprising a flexible diaphragm 93, subject on one side to the pressure in diaphragm chamber 94, and a valve 95, contained in valve and diaphragm chamber 96, and adapted to be operated by said diaphragm.

40 The brake valve device 1 may comprise an upper casing section, a lower casing section and an intermediate casing section and contained in the intermediate casing section is a valve chamber 97 containing an upper rotary valve 98 and 50 a lower rotary valve 99, both adapted to be operated by handle 100. The upper casing section contains a release valve device comprising a piston 101 subject on one side to the pressure in piston chamber 102, and a valve 103, contained 55 in valve chamber 104 and adapted to be operated by piston 101.

45 The acknowledging valve device 2 may comprise a casing having a valve chamber 105 containing a rotary valve 106 adapted to be operated 60 by handle 107.

50 The equalizing discharge valve mechanism for the brake valve device is also the equalizing discharge valve mechanism of the train control apparatus and is associated with the brake application valve unit, as hereinbefore described.

55 With the brake valve in running position, as shown in Fig. 1, the brake pipe 108 is maintained charged to the standard pressure from the main reservoir 109, from which fluid flows through 60 pipe and passage 110 to valve chamber 70 and thence, with the slide valve 69 in the normal release position as shown, through pipe and passage 111 to the rotary valve chamber 97 of the brake valve device. In running position, fluid is sup-

plied from the pipe 111 through pipe 112 and the usual pressure reducing feed valve device 113 to the brake pipe 108 by way of cavity 114 in the rotary valve 99.

5 The brake pipe 108 is connected in the usual manner to the piston chamber 92 of the equalizing discharge valve mechanism and is also connected to the diaphragm chamber 58 of the reduction ensuring valve device. 5

10 A suppression limiting reservoir 115 is connected to pipe and passage 116 which leads to diaphragm chamber 57 of the reduction ensuring valve device and said reservoir is charged with fluid under pressure from the brake pipe 108 through passage 117 in the brake valve device and cavity 118 in the rotary valve 98. 10

15 A reduction reservoir 119 is connected in the running position of the brake valve device through pipe 120 and cavity 121 in the rotary valve 98 with an atmospheric exhaust 122.

20 The equalizing reservoir 90 and the piston chamber 88 of the equalizing discharge valve mechanism are charged to brake pipe pressure by way of cavity 123 in the rotary valve 99, pipe 25 and passage 124, and cavity 125 in application slide valve 69.

25 The valve chamber 74 of the pilot valve device is charged with fluid at a pressure less than main reservoir pressure by way of a feed or reducing valve device 126 and pipe and passage 127. The valve chamber 86 of the split reduction cut-off valve device is also charged with fluid from passage 127, as well as the piston chamber 105 of the acknowledging valve 2.

30 Assuming that the train is running under a high speed signal indication, the high speed magnet 43 will be energized and the medium speed magnet 46 deenergized. The valve 44 will then be seated and the valve 45 unseated so as to supply fluid at feed valve pressure from pipe 127 to passage 128, leading to piston chamber 19 of the high speed valve device, and since the valve chamber 21 is also charged with fluid from the pipe and passage 127, the piston 18 will be held 35 in its inner position by spring 129. In this position, the slide valve 20 opens communication from valve chamber 21 through passage 130 to diaphragm chamber 32 of the high to medium timing valve device and to the high to medium reservoir 131, so that said chamber and reservoir are charged with fluid at feed valve pressure. The diaphragm 31 then moves the valve 34 to close communication from passage 132 to passage 133. Passage 132 leads from piston chamber 72 of the pilot valve device past the open valve 64 of the application suppressing valve device and passage 133 leads to the medium speed governor valve 13, so that communication is now cut off from the pilot piston 71 to the medium speed governor valve 13. 40

45 In the high speed position of slide valve 20, the diaphragm chamber 37 of the medium to low timing valve device and the medium to low reservoir 134 are also charged with feed valve pressure from valve chamber 21 through port 135 in slide valve 20 and passage 136, so that diaphragm 36 is operated to close valve 39 and open valve 41. Fluid at feed valve pressure is then supplied from feed valve passage 127 to passage 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

voir 139 through passage 140 and cavity 141 in slide valve 24 with an atmospheric exhaust port.

With the train running at a speed above the medium speed limit, the speed governor will operate the cross head 12 so that the medium speed governor valve 13 will be open, connecting pipe and passage 133 to the atmosphere. Pipe and passage 133 leads to piston chamber 84 of the split reduction cut-out valve device, so that piston 83 will be shifted to its outer position by feed valve pressure in valve chamber 86. 5

In this position, the slide valve 85, through cavity 142, connects passage 143, leading to the second reduction reservoir 55 with passage 144 leading to the first reduction reservoir 54, so that 15 the two reservoirs operate as a single reservoir, the split reduction feature, to be hereinafter described, being thus cut out of action, passage 144 is connected to exhaust port 149 through a port 150 in slide valve 69, when the application 20 piston 67 is in its normal release position, so that both reduction reservoirs 54 and 55 are now maintained at atmospheric pressure. 25

The pipe and passage 132 is connected to the high speed governor valve 15, so that if the speed of the train should exceed the high speed limit, the speed governor will operate the cross head 12 to open the high speed valve 15. When valve 15 is opened fluid under pressure is vented to the atmosphere from pipe and passage 132 and the piston chamber 72 of the pilot valve device, causing the movement of piston 71 to its outer position by feed valve pressure in valve chamber 74. In this position, communication from valve chamber 70 through passage 145, cavity 146 and 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

Fluid under pressure being thus vented from piston chamber 68, the application piston 67 will be shifted to its outer position by the fluid pressure in valve chamber 70. In this position of the application slide valve 69, the port 150 connects passage 89, leading to the equalizing reservoir 90 and the equalizing discharge piston chamber 88 with passage 144, leading to the first reduction reservoir 54. 40 45

The port 150 includes a restricted portion 151 corresponding with the usual preliminary discharge port of the standard brake valve, so that fluid is vented from the equalizing reservoir at the same rate as would be the case with a brake valve when moved to service application position. The combined volumes of the first and the second reduction reservoirs are such that the 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

The piston 87 is operated by the reduction in equalizing reservoir pressure to open the discharge valve 91, so that fluid is vented from the brake pipe 108 to a passage 152, leading to piston chamber 76 of the reduction timing valve device. Piston 75 is then shifted outwardly, so that an exhaust passage 153 having a restriction 157 is opened to chamber 76. Fluid is also vented from the brake pipe by way of passage 154 containing a non-return check valve 155 and a restricted 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

The areas of the three restricted exhaust ports 75

157, 156, and 159 are such that the rate of discharge from the brake pipe is equal to that produced when the equalizing discharge valve is fully opened in the standard brake valve. The 5 pressure of fluid vented from the brake pipe through passage 154 acts in chamber 94 of the reduction safety valve device, so that diaphragm 93 is moved upwardly to close the valve 95.

The brake pipe pressure will continue to reduce 10 by operation of the discharge valve 91 until a full service application of the brakes has been effected or until the speed of the train has been reduced below the high speed limit. If the speed of the train has been reduced below the high 15 speed limit, the high speed governor valve 15 will close and the engineer may release the brakes by turning the brake valve handle 100 to lap position for a short period and then to release position. When the application slide valve 69 is 20 moved to application position, a pipe and passage 160, leading to the valve chamber 104 of the release pilot valve device is connected, through cavity 161, with passage 132.

In running position of the brake valve, fluid 25 under pressure is supplied through a port 162 to piston chamber 102, so that the piston 101 operates to hold the valve 103 open, connecting passage 160 with the atmosphere.

As a consequence, so long as the brake valve 30 remains in running position, the passage 132 and piston chamber 72 of the pilot piston valve device will be open to the atmosphere, even though the high speed governor valve 15 should close and the pilot piston 71 will be maintained in its brake 35 applying position.

When the engineer moves the brake valve handle to lap position, the piston chamber 102 is vented to the atmosphere, permitting the valve 103 to move so as to cut off the exhaust through 40 passage 160. The pressure in piston chamber 72 can then build up by equalization through port 163 in piston 71, permitting spring 164 to shift piston 71 back to release position.

In this position, fluid is supplied from valve 45 chamber 70 through passage 145, cavity 146, and passage 147 to piston chamber 68, thus equalizing the fluid pressures on opposite sides of piston 67 and permitting spring 165 to shift piston 67 to release position. The engineer can now release 50 the brakes by moving the brake valve to release position, in which the brake pipe is recharged in the usual manner.

If the signal indication be changed from high 55 speed to medium speed and the train is running at a speed exceeding the medium speed limit, the indication should be acknowledged at once by the engineer making a full service application of the brakes to reduce the speed of the train below the medium speed limit, it being noted that under 60 the above conditions the acknowledging valve handle 107 need not be operated.

If the engineer fails to acknowledge the signal indication by making a full service application of the brakes, and if the full service reduction in 65 brake pipe pressure is not effected in a predetermined time, the train control apparatus will then operate to produce an application of the brakes.

When the engineer moves the brake valve to 70 service application position, the upper rotary valve 98 connects pipe 116, through a cavity in the rotary valve, with pipe 120, so that fluid is vented from the normally charged suppression reservoir 115 to the reduction reservoir 119, which 75 is now at atmospheric pressure. The pressures

in the two reservoirs equalize at a predetermined pressure, say fifty pounds, when the standard brake pipe pressure is seventy pounds, so that the reduction in pressure amounts to twenty pounds.

The pipe and passage 116 is connected to the diaphragm chamber 57 of the reduction ensuring valve device so that the pressure in said chamber is also reduced twenty pounds. In service position of the brake valve, pipe 124 is connected, through a cavity in the lower rotary valve 99 with 10 an atmospheric exhaust port, so that fluid is vented from the equalizing reservoir 90 and the piston chamber 88 of the equalizing discharge valve mechanism by way of passage 89, cavity 125 in application slide valve 69 and pipe 124. 15

The reduction in pressure in the equalizing reservoir causes the movement of the equalizing piston 87 by the higher brake pipe pressure acting in chamber 92, so that the valve 91 is opened to discharge fluid under pressure from the brake 20 pipe 108 and thereby effect an application of the brakes.

Fluid is vented from the brake pipe by the opening of the discharge valve 91 through passage 152 to piston chamber 76 of the reduction 25 timing valve device. Piston 75 is operated to close the valve 77 and uncover port 153 so that fluid is vented at this point at a rate determined by the restricted port 157. Fluid is also vented through passage 154, past the check valve 155 and out at 30 the restricted atmospheric port 156. From passage 152, the discharge from the brake pipe flows through a cavity 166 and passage 167 past check valve 168 to chamber 63 of the application suppressing valve device and thence to timing reservoir No. 2 and valve chamber 61 by way of passage 169. The pressure in chamber 57 being the reduced suppression reservoir pressure, the higher brake pipe pressure in chamber 58 holds the diaphragm 56 in its lower position, opening the valve 40 59 and seating valve 60. Fluid is therefore vented from passage 169 past the valve 59 through a restricted exhaust port 170.

The venting of fluid from the brake pipe to chamber 63 causes the upward movement of 45 diaphragm 62, so as to unseat valve 65 and seat the valve 64. The seating of valve 64 cuts off communication through passage 132, so that the pilot piston 71 is cut off from the medium speed governor valve 13 and thus the operation of the 50 pilot valve device and the application valve device is prevented so long as the valve 64 of the application suppressing valve device remains seated.

If the brake pipe pressure is reduced a predetermined amount, preferably a full service reduction, or about twenty-five pounds, where the standard brake pipe pressure is seventy pounds, the brake pipe pressure in chamber 58 being slightly less than the suppression reservoir pressure in chamber 57, the diaphragm 56 will be operated to open valve 60 and close valve 59. The closing of valve 59 cuts off the venting of fluid from the chamber 63 and the timing reservoir No. 2, so that the pressure therein is bottled up and the diaphragm is held in position to maintain the valve 64 closed, thus preventing the operation of the pilot piston valve device.

When the reduction ensuring valve device has been operated upon a predetermined reduction in brake pipe pressure to close the valve 59, the valve 60 will be unseated, so that fluid under pressure will then be supplied from the brake pipe to the chamber 63 by way of passage 108, past the open valve 60, to passage 169 and thence through 75

a by-pass around the check valve 168 to chamber 63. The pressure in chamber 63 will thus be maintained after the equalizing discharge valve 91 is closed and thereby the suppressing valve device will be maintained in its suppressing position, so long as the brakes remain applied.

If the reduction in brake pipe pressure is less than the predetermined amount, then when the discharge valve 91 closes, since the discharge of fluid from the brake pipe is cut off, the pressure in chamber 63 and in the timing reservoir No. 2 will bleed down through the restricted port 170 and after a predetermined short period of time, the diaphragm will be permitted to move downwardly and the valve 64 will be opened to establish communication through the passage 132.

If under the above condition, the speed of the train exceeds the medium speed limit, the passage 132 will be connected to the open medium speed governor valve 13 as follows.

Upon receiving a medium speed signal indication, the high speed magnet 43 will be deenergized and the medium speed magnet 46 energized. When the high speed magnet 43 is deenergized, the valve 45 will be seated and the valve 44 opened, so that fluid is vented from piston chamber 19 of the high speed piston 18, through passage 128 to the atmospheric exhaust controlled by valve 44. The high speed piston 18 consequently shifts the valve 20 to its outer position.

The energization of the medium speed magnet 46 operates to close the valve 47 and open the valve 48, so that passage 136 leading to chamber 37 of the medium to low timing valve device 35 and to the medium to low timing reservoir 134 is connected with feed valve passage 127 through cavity 171 in slide valve 20 and passage 172. The medium to low speed timing reservoir 134 and chamber 37 of the medium to low timing valve 40 device are thus maintained charged with fluid at feed valve pressure while the train control apparatus is operating under a medium speed signal indication.

In the outer position of the slide valve 20, the high to medium reservoir 131 and the chamber 32 of the high to medium timing valve device are connected to the high to medium blow down timing valve 16 by way of passage 130, cavity 173 in slide valve 20 and passage 174.

When the pressure in the reservoir 131 and chamber 32 has been reduced to a predetermined degree, dependent on the speed of the train and the consequent size of vent opening created by the valve 16, the diaphragm 31 will be operated so as to cause the double beat valve 34 to open communication from passage 132 to passage 133. This establishes communication from the pilot piston chamber 72 to the medium speed governor valve 13, and if the speed of the train exceeds the medium speed limit, the valve 13 will be opened, so that fluid is vented from piston chamber 72.

The pilot valve device will then be operated to vent fluid from piston chamber 68 of the application valve device and further operation of the parts to effect a reduction in brake pipe pressure and an application of the brakes will be the same as hereinbefore described in connection with a train running in a high speed block and exceeding the high speed limit.

It will thus be seen that if the engineer makes a service application of the brakes but fails to make a full service reduction in brake pipe pressure, the automatic train control apparatus will be cut in and will operate to effect a further re-

duction in brake pipe pressure, provided the train is running at a high speed exceeding the medium speed limit. In fact, when the brakes are applied by operation of the train control apparatus as above described, a full service reduction in brake pipe pressure is made in addition to whatever reduction, less than the full service reduction, which may have been previously effected by the engineer.

It is desirable that the engineer be permitted to make a split reduction in brake pipe pressure if he wishes to, that is to say, first a light reduction in brake pipe pressure and then a heavy reduction, and provision is made for this by providing the timing reservoir No. 2 which functions as follows: When the first reduction in brake pipe pressure is made by the engineer and as soon as the discharge from the brake pipe ceases through the closing of the discharge valve 91, the valve 59 will remain open, since the reduction in brake pipe pressure has not been sufficient to effect the movement of the diaphragm 56 to close the valve 59 but the diaphragm 62 will not be immediately operated, because said diaphragm will remain in its upper position, until the pressure in the timing reservoir No. 2 and in chamber 63 has been reduced by escape through the restricted port 170. The delay in the operation of diaphragm 62 is sufficient to permit the engineer to move the brake valve handle from lap position after the first reduction in brake pipe pressure ceases, back to service position, for the purpose of effecting the second reduction in brake pipe pressure and if the second reduction in brake pipe pressure is sufficient to produce a full service reduction in brake pipe pressure the operation of the train control apparatus to effect an application of the brakes will be suppressed.

If the engineer does not make the second reduction in brake pipe pressure within the time permitted by the venting of pressure from the timing reservoir No. 2 and to a degree corresponding with a full service application of the brakes, the train control apparatus will function, as will be understood.

It will be further understood that should the engineer fail to make any brake application, the train control apparatus will function as hereinbefore described, if the speed exceeds the medium speed limit, to effect an application of the brakes.

If the brake application is produced by the operation of the train control apparatus instead of by the engineer manipulating the brake valve, a delay penalty is imposed by requiring a longer time to effect the release of the brakes. This is due to the fact that when the train control apparatus functions, the pipe and passage 132 is vented by the unseating of the medium speed valve 13 and before the brakes can be released, the medium speed valve must close and the pipe and passage 132 must be recharged. The additional time required to recharge the pipe 132 before the brakes can be released provides the time penalty, when the engineer fails to apply the brakes upon passing a signal indication set at medium speed.

The passage 132 is recharged through the restricted port 163 in piston 71 and also by way of a restricted port 175 leading from the feed valve passage 127 to passage 132.

In order to release the brakes after the brakes have been applied by operation of the train control apparatus, the brake valve handle must first be moved to lap position, in which the supply of fluid to the chamber 102 of the release pilot valve device is cut off and said chamber is connected to

- the exhaust through a cavity in the upper rotary valve 98. The piston 101 then shifts the valve 103 to its seat, cutting off the exhaust port 176 from the passage 160. Passage 160 is connected in the application position of application slide valve 69 through cavity 161 with passage 132, so that closing the exhaust port 176 permits the passage 132 to be recharged as soon as the medium speed governor valve 13 closes.
- 10 When the passage 132 has been recharged and the application valve device has been returned to release position by the movement of the pilot valve device to release position, the brake valve handle may be moved to release position, so as 15 to recharge the brake pipe and thus effect the release of the brakes.

When the speed of the train is below the medium speed limit, the medium speed governor valve 13 will be closed and the passage 133 being 20 cut off from the atmosphere, fluid pressure equalizes through a restricted port 177 in the piston 83 of the split reduction cut-out valve device to the piston chamber 84, permitting spring 178 to move piston 83 and valve 85 to their inner 25 position, in which the split reduction feature is cut in, as will be hereinafter described.

When a train receives a low speed signal indication, the engineer, upon noting the change in the signal indication should move the acknowledging 30 device handle 107 to acknowledging position, and should make an application of the brakes to reduce the speed of the train below the low speed limit and this action must be effected within a predetermined period of time as determined by the blowing down of the medium to low 35 reservoir pressure.

With the acknowledging handle 107 in its normal position, as shown in Fig. 1, the acknowledging reservoir 179 will be connected, through 40 a cavity 180 in the rotary valve 106, with feed valve pipe 127, so that said reservoir is normally charged with fluid under pressure. When the handle 107 is turned to acknowledging position, the reservoir 179 is connected, through a cavity 45 in the rotary valve 106, with pipe and passage 181, communication through which is established by way of cavity 182 in the application slide valve 69 when said valve is in release position.

Fluid under pressure is then supplied through 50 pipe and passage 181 to piston chamber 26^a of the acknowledging pilot valve device and the piston 26 is shifted to its inner position, opening the valve 29 and causing the valve piston 27 to cut off communication from passage 140 leading to stop 55 reservoir 139 to the seat of slide valve 24. The opening of valve 29 permits flow of fluid under pressure from valve chamber 21, which is connected by passage 183 with chamber 30, to passage 140, so that the stop reservoir 139 is charged 60 with fluid under pressure.

The piston chamber 26^a is connected to the atmosphere through a restricted port 184, of such size that the chamber 26^a and the acknowledging reservoir 179 will blow down in a predetermined 65 period of time, such as thirty seconds. After the pressure has been reduced, the piston 26 will return to its normal outer position. The result of acknowledging the low speed signal indication will depend upon the speed of the train at the 70 time the signal indication is received.

Before describing the results of acknowledging or not acknowledging when a low speed indication is received we will describe the general operation of the apparatus upon receiving a low speed 75 signal indication. Referring more particularly

to the diagram, Fig. 4, when a low speed indication is received, the medium speed magnet 46 is deenergized, and the high speed magnet 43 will remain deenergized, as it was under a medium speed indication.

The high speed piston 18 will therefore remain in its outer position, as was the case when under a medium speed indication and the medium speed magnet 46 being deenergized, the valve 48 will be seated and the valve 47 opened, the chamber 37 of the medium to low timing valve device and the medium to low reservoir 134 will be connected to the medium to low blow down timing valve 17 by way of passage 136, cavity 171 in slide valve 20, and through passage 172, past the open valve 47 to the blow down valve 17. When the pressure in the reservoir 134 has been blown down to a predetermined degree, dependent upon the speed of the train and the consequent size of the vent opening created by the operation of valve 17, the diaphragm 36 will be operated, so that the valve 41 will close and the valve 39 open. Fluid is then vented from piston chamber 23 through passage 137 past the open valve 39 to the atmosphere, and the medium speed piston 22 25 will be shifted to its outer position, moving valve 24 to its outer position.

In this position, the low speed governor valve 14 is connected to pipe and passage 132 through 30 passage 184 and cavity 185 in slide valve 24. Passage 132 contains a check valve 186 for preventing flow through said passage in one direction. Cavity 185 also connects passage 132 with passage 140, so that if the acknowledging piston 26 has not been moved by the engineer acknowledging the signal indication, the passage 132 will be connected to the stop reservoir 139.

If the engineer fails to acknowledge the low speed signal indication by moving the handle 107, but makes an application of the brakes by operating the brake valve handle 100, the acknowledging piston 26 will remain in its outer position, so that the passage 132 is connected to the stop reservoir 139, as before explained.

If the train is running at a speed less than the 45 low speed limit when a low speed signal indication is received, it is not necessary to make an application of the brakes, but the engineer must acknowledge the signal indication by moving the acknowledging handle 107 and if he fails to do so, 50 then when a low speed signal indication is received, the passage 132 will be connected to the stop reservoir 139 and even though the low speed governor valve 14 be closed, the reservoir 139 being at atmospheric pressure, the passage 132 55 will be vented to the reservoir 139 and this will cause the operation of the pilot piston 71 and thereby the operation of the application piston 67 to effect an application of the brakes in the manner hereinbefore described except in this 60 case, due to the medium speed valve 13 being closed, the split reduction cut-out piston 83 will be in its inner position, so that the reduction in brake pipe pressure will be effected in two stages.

When in the split reduction position, the slide valve 85 cuts off communication from passage 143 to passage 144 and thus between the reduction reservoirs 54 and 55, so that upon movement of the application slide valve 69 to application position, the equalizing reservoir 90 is equalized only 70 into the reduction reservoir 54 by way of passage 89, cavity 150 in slide valve 69 and passage 144.

The reduction in equalizing reservoir pressure thus effected operates the equalizing discharge 75

5 piston 87 to open the discharge valve 91, so that fluid is vented from the brake pipe 108 to passage 152. Thence the vented fluid flows to chamber 76 and operates the valve piston 75 to open 5 the restricted vent port 157 and to close the valve 77. Fluid is also vented through passage 154, past the check valve 155, to the timing reservoir No. 1, to the restricted vent port 156 and also to the chamber 94 of the diaphragm 93.

10 Fluid pressure equalizing into the reduction reservoir 54 also flows from passage 144 to the under side of the reduction hold back valve 79 and also to the outer seated area of said valve piston, while the inner seated area of said valve 10 piston is open to the reduction reservoir 55, which is now at atmospheric pressure, by way of passage 143. The valve piston 79 will therefore be maintained in its upper position by the higher fluid pressure acting below said piston, 15 aided by the spring 187.

15 When the discharge valve 91 closes, due to the brake pipe pressure being reduced to equal the reduced pressure in the equalizing reservoir, as effected by the reduction reservoir 54, the venting 20 of brake pipe pressure ceases, and the timing valve piston 75 will return to its upper position. The check valve 77 will then unseat, permitting the venting of fluid from the under side of piston 79 through passage 188, past the open valve 77 25 to exhaust passage 153. The pressure in reduction reservoir 54, acting on the outer exposed upper seated area of valve piston 79 then operates to shift the valve piston downwardly to its lower seat. The downward movement of the valve 30 piston unseats the valve 81, so that the chamber within the lower seat of the valve piston is vented to the atmosphere to maintain the valve piston in its lower seated position. The downward movement of the valve piston 79 opens communication 35 from the reduction reservoir 54 through passage 144 to the reduction reservoir 55 through passage 143, so that a further reduction in pressure in the equalizing reservoir is effected.

40 This further reduction in equalizing reservoir pressure operates to move the equalizing discharge piston 87 to open the discharge valve 91, so that the brake pipe pressure is further reduced. The combined volumes of the reduction reservoirs 54 and 55 is such that a full service 45 reduction in brake pipe pressure is effected.

45 The No. 1 timing reservoir and the reduction safety valve will function only in case the pressure at the under side of the valve piston 79 has not been discharged after a predetermined period 50 of time.

55 Due to possible leakage after the discharge valve 91 seats after the first reduction in brake pipe pressure has been made, the piston 75 may not move up so as to open the valve 77, with the result that the valve piston 79 will not be operated and the safety valve then functions to vent fluid from the piston 79.

60 When the first reduction in brake pipe pressure is made, fluid is supplied to passage 154 as hereinbefore described and flows to the diaphragm chamber 94 of the safety valve device. The diaphragm 93 then operates to seat the valve 95.

65 Fluid supplied to passage 154 also charges the timing reservoir No. 1 and it will now be evident 70 that when the discharge valve 91 closes after the first reduction, if the piston 75 fails to lift, due to leakage past the discharge valve 91, then after the time required for the timing reservoir No. 1 to leak down by way of the restricted exhaust port 156, the diaphragm 93 will move down-

wardly, permitting the valve 96 to open, so as to vent fluid from the under face of piston 79. Said piston will then be operated to open communication between the reduction reservoirs 54 and 55, to cause a full service reduction in brake pipe 5 pressure as would have been the case had the valve 77 been opened by the operation of the reduction timing valve piston 75.

75 It will be understood that since the split reduction cut-out valve device is moved to its cut-in position when the medium speed governor valve is closed due to the speed of the train being less than the medium speed limit, the reduction of brake pipe pressure in two stages, as above described, will be effective whenever the brakes 10 are automatically applied at any speed less than the medium speed limit.

15 In order to release, the brake valve handle must be first moved to lap position, as in releasing after passing a medium speed indication, but in this 20 case, it will be noted that in addition to requiring the recharge of the application pipe 132, the stop reservoir 139 must also be recharged, before the pilot piston 71 will be moved back to release position. As a result, it requires a longer period 25 of time to effect the release after passing a low speed signal indication, if the indication is not acknowledged, and since a full service application of the brakes was made at a relatively low speed, the train will be brought to a stop before 30 the brakes can be released. This operates as a penalty for failure of the engineer to acknowledge a low speed signal indication.

35 Furthermore, should the train be running at less than the low speed limit upon passing a low speed signal indication, the brakes will be applied, if the engineer fails to acknowledge the indication, so that if the engineer should happen to be incapacitated when a low speed indication is received, the train will be brought to a stop 40 even if the speed is less than the low speed limit.

45 If the engineer acknowledges the low speed signal indication by moving the handle 107 to acknowledging position, and the speed of the train is under the low speed limit, the stop reservoir 139 will be charged with fluid under pressure as hereinbefore described in the first portion of the description of operation when the train receives a low speed signal indication.

50 With the stop reservoir charged with fluid under pressure, when the parts move to low speed position, in which the medium speed slide valve 24 connects the stop reservoir 139 with the application pipe 132, the low speed governor valve 14 being closed, since the train is running at less than the low speed limit, the pressure in the application pipe 132 will be maintained by the pressure in the stop reservoir, so that the application portion of the train control apparatus will not be operated to effect an application of the 55 brakes.

60 If the speed of the train when a low speed signal indication is received exceeds the low speed limit, the engineer should make an application of the brakes as well as acknowledge the signal indication and sufficient to reduce the speed of the train to less than the low speed limit before the time period expires which is provided by operation of the medium to low speed timing valve device. This will prevent operation of the train 65 control apparatus to effect an application of the brakes and the brakes can thereafter be promptly released by operating the brake valve device in the usual manner. The train may then proceed 70 at a speed less than the low speed limit.

The object of providing the restricted port 175 for charging the application pipe 132 is to prevent operation of the application pilot piston after the engineer has made an application of the brakes. When the engineer applies the brakes, the suppression valve 64 is seated, cutting off communication through pipe 132, and after the governor valve closes due to the speed of the train having been reduced below the indicated speed limit, that portion of the pipe and passage 132 between the governor valve and the valve 64 would be at atmospheric pressure, if the feed passage 175 were not employed, so that when the engineer released the brakes, causing the valve 64 to unseat, the pressure in pilot piston chamber 72 would be vented to that portion of the application pipe 132 between the valve 64 and the governor controlled valve, and this would operate to cause an application of the brakes by operation of the application portion of the train control apparatus. By feeding fluid under pressure into the pipe 132 through restricted passage 175, the above undesired action is prevented, since the application pipe will be maintained charged after the governor valve closes.

By employing an additional rotary valve in the brake valve device, the existing standard brake valve device with the usual rotary valve may be retained and the additional features employed in connection with the automatic train control are provided by adding a section to the existing brake valve which includes an additional rotary valve for controlling the functioning of the train control apparatus.

35 By employing a pilot valve device for controlling the operation of the application valve device, the application valve device may be controlled by full main reservoir pressure and also provides for the supply of fluid at main reservoir pressure to the brake valve device, while the other parts of the train control apparatus are subject to fluid at feed valve pressure or a pressure less than the main reservoir pressure. In other words, the pilot valve device provides means for separating the application valve device from the other parts of the train control apparatus with respect to fluid pressure.

The reason it is desired to employ fluid pressure in the train control apparatus which has been reduced from the main reservoir pressure is that at the reduced pressure, moisture will not precipitate or condense out of the fluid so readily and this will prevent possible clogging of the passages with moisture.

55 Having now described our invention what we claim as new and desire to secure by Letters Patent, is:—

1. In an automatic train control equipment, the combination with automatic apparatus operable to effect an application of the brakes, of a brake pipe, manually operable means for reducing the brake pipe pressure to effect an application of the brakes, and valve means operated by fluid vented from the brake pipe by operation of said manually operable means for preventing the operation of said automatic apparatus.

2. In an automatic train control equipment, the combination with automatic apparatus operable to effect an application of the brakes, of a brake pipe, manually operable means for reducing the brake pipe pressure to effect an application of the brakes, valve means subject to the fluid pressure in a chamber and operated by fluid vented from the brake pipe to said chamber by operation of said manually operable means for pre-

venting the operation of said automatic apparatus, and an additional valve means, subject to brake pipe pressure for venting fluid from said chamber and operated upon a predetermined reduction in brake pipe pressure for closing communication through which fluid is vented from said chamber.

3. In an automatic train control equipment, the combination with automatic apparatus operable to effect an application of the brakes, of a brake pipe, manually operable means for reducing the brake pipe pressure to effect an application of the brakes, valve means subject to the fluid pressure in a chamber and operated by fluid vented from the brake pipe to said chamber by operation of said manually operable means for preventing the operation of said automatic apparatus, and an additional valve means subject to brake pipe pressure, and controlling communication from said chamber to a restricted exhaust port and operated upon a predetermined reduction in brake pipe pressure for closing said communication.

4. In an automatic train control equipment, the combination with a valve mechanism operated upon a reduction in fluid pressure for effecting an automatic application of the brakes, of a brake pipe, a valve for controlling communication through which the fluid pressure on said valve mechanism is reduced, a movable abutment, subject to the pressure in a chamber, for operating said valve, a valve for controlling communication from said chamber to an exhaust port, and a movable abutment subject to brake pipe pressure for operating said valve.

5. In an automatic train control apparatus, the combination with a brake pipe and a valve mechanism operated upon a reduction in fluid pressure for effecting a reduction in brake pipe pressure, of a valve for controlling communication through which the fluid pressure on said valve mechanism is reduced, a movable abutment, subject to the pressure in a chamber and operated by fluid vented from the brake pipe for closing said valve, an additional valve for controlling communication from said chamber to an exhaust port, and a movable abutment, subject to brake pipe pressure and operated upon a predetermined reduction in brake pipe pressure for closing said additional valve.

6. In an automatic train control apparatus, the combination with a brake pipe and a valve mechanism operated upon a reduction in fluid pressure for effecting a reduction in brake pipe pressure, of a valve for controlling communication through which the fluid pressure on said valve mechanism is reduced, a movable abutment, subject to the pressure in a chamber and operated by fluid vented from the brake pipe for closing said valve, an additional valve for controlling communication from said chamber to an exhaust port, a movable abutment, subject to brake pipe pressure and operated upon a predetermined reduction in brake pipe pressure for closing said valve, and manually operable means for effecting a reduction in brake pipe pressure.

7. In an automatic train control apparatus, the combination with a brake pipe and a valve mechanism operated upon a reduction in fluid pressure, of manually operable means for effecting a reduction in brake pipe pressure and means for controlling communication through which the fluid pressure on said valve mechanism is reduced and operated upon failure of said manually oper-

able means to effect a predetermined reduction in brake pipe pressure within a predetermined period of time for opening said communication.

8. In an automatic train control apparatus, the combination with automatically operable means for effecting an application of the brakes, a brake pipe, manually operable means for effecting a reduction in brake pipe pressure to cause an application of the brakes, and means operative while the brake pipe pressure is reducing and for a limited period of time after the reduction in brake pipe pressure ceases to prevent the operation of said automatically operable means to effect an application of the brakes.

9. In an automatic train control apparatus, the combination with a brake pipe, a reduction in pressure in which is adapted to effect an application of the brakes, automatic means for effecting a reduction in brake pipe pressure, and manually operable means for effecting a reduction in brake pipe pressure, of means operating to prevent the automatic means from effecting a reduction in brake pipe pressure for a limited period of time after a reduction in brake pipe pressure is effected by said manually operable means.

10. In an automatic train control apparatus, the combination with a brake pipe, a reduction in pressure in which is adapted to effect an application of the brakes, automatic means for effecting a reduction in brake pipe pressure, and manually operable means for effecting a reduction in brake pipe pressure, of means operating to prevent the automatic means from effecting a reduction in brake pipe pressure for a limited period of time after a reduction in brake pipe pressure is effected by said manually operable means and for further preventing the operation of said automatic means, if a second reduction in brake pipe pressure, sufficient to reduce the brake pipe pressure to a predetermined degree, is effected by the manually operable means within said period of time.

11. In an automatic train control apparatus, the combination with a brake pipe, a reduction in pressure in which is adapted to effect an application of the brakes, automatic means for effecting a reduction in brake pipe pressure, and manually operable means for effecting a reduction in brake pipe pressure, of means operating to prevent the automatic means from effecting a reduction in brake pipe pressure for a limited period of time after a reduction in brake pipe pressure is effected by said manually operable means and for further preventing the operation of said automatic means, if a second reduction in brake pipe pressure is effected by the manually operable means within said period of time.

12. In an automatic train control apparatus, the combination with a brake pipe, automatic train controlled means for effecting a reduction in brake pipe pressure, and manually operable means for effecting a reduction in brake pipe pressure, of means for preventing the operation of said automatic means to effect a reduction in brake pipe pressure if a predetermined reduction in brake pipe pressure is effected by said manually operable means, and means for maintaining said preventing means in the position for preventing operation of the automatic means for a limited period of time, if less than said predetermined reduction in brake pipe pressure is effected.

13. In an automatic train control apparatus, the combination with a brake pipe, automatic train controlled means for effecting a reduction

in brake pipe pressure, and manually operable means for effecting a reduction in brake pipe pressure, of a valve effective to prevent operation of said automatic means, means operative when the brake pipe pressure is reduced by operation of said manually operable means for operating said valve, and means operative to maintain said valve in its position for preventing operation of the automatic means for a predetermined time after the reduction in brake pipe pressure ceases.

14. In an automatic train control apparatus, the combination with a brake pipe, an equalizing reservoir, a valve device subject to the opposing pressures of the brake pipe and the equalizing reservoir and operated upon a reduction in pressure in the equalizing reservoir for venting fluid from the brake pipe, of manually operated means for venting fluid from the equalizing reservoir, automatic means for venting fluid from said reservoir, and a valve mechanism operated by fluid vented from the brake pipe by operation of said valve device for preventing the operation of said automatic means.

15. In an automatic train control apparatus, the combination with a main reservoir and a brake application valve device subject to fluid at main reservoir pressure, of a pilot valve device subject to fluid at a reduced pressure less than main reservoir pressure for controlling the operation of said application valve device.

16. In an automatic train control apparatus, the combination with a main reservoir and a brake application valve device comprising a valve and a piston subject on opposite sides to fluid at main reservoir pressure, of a pilot valve device comprising a piston subject on opposite sides to fluid at a pressure less than main reservoir pressure and a valve operated by said piston upon a reduction in pressure thereon for venting fluid from one side of said application piston.

17. In an automatic train control apparatus, the combination with a main reservoir and a brake application valve device comprising a valve and a piston subject on one side to fluid at main reservoir pressure, of a pilot valve device comprising a piston subject on opposite sides to fluid at a pressure less than main reservoir pressure and a valve operated by said piston and having one position for supplying fluid at main reservoir pressure to the opposite side of said application piston and another position in which fluid is vented from said opposite side.

18. In an automatic train control apparatus, the combination with a brake pipe, of means for automatically effecting a reduction in brake pipe pressure in two stages and including a first reduction reservoir into which fluid is vented by operation of said means to effect the first reduction in brake pipe pressure and a second reduction reservoir into which fluid is vented to effect the second reduction in brake pipe pressure and a valve device controlled in accordance with the speed of the train for connecting the first reduction reservoir to the second reduction reservoir to thereby render said means ineffective to cause a reduction in brake pipe pressure in two stages.

19. In an automatic train control apparatus, the combination with a brake pipe, an equalizing reservoir, and a valve device subject to the opposing pressures of the brake pipe and the equalizing reservoir for venting fluid from the brake pipe, of two reduction reservoirs, valve means for first venting fluid from the equalizing reservoir to one reduction reservoir and then to the other

- reduction reservoir, and a valve device controlled in accordance with the speed of the train and having a position for connecting one reduction reservoir to the other reduction reservoir.
5. 20. The combination with a brake valve device having a rotary valve and an operating handle therefor for controlling the brakes, of an automatic train control apparatus and an additional valve controlled by said operating handle and 10 operative to influence the functioning of the train control apparatus.
21. The combination with a brake valve device having a rotary valve and an operating handle therefor for controlling the brakes, of an automatic train control apparatus and an additional 15 rotary valve operable by said handle for controlling the train control apparatus to the extent that the same is manually controlled.
22. In an automatic train control apparatus, 20 the combination with mechanism for automatically effecting an application of the brakes, of a brake valve device comprising a rotary valve for controlling the brakes, a handle for operating said valve, and an additional valve operable by 25 said handle and controlling means for effecting the movement of said mechanism to release the brakes.
23. In an automatic train control apparatus, 30 the combination with mechanism for automatically effecting an application of the brakes, of a brake valve device comprising a rotary valve for controlling the brakes, a handle for operating said valve, an additional rotary valve operable by said handle, and means controlled by 35 said additional rotary valve for controlling the release of the brakes when applied by operation of said automatic mechanism.
24. The combination with a brake pipe, of a 40 valve mechanism for making a first and then a second reduction in brake pipe pressure comprising valve means for initiating the second reduction in brake pipe pressure, a valve device operating upon completion of the first reduction in brake pipe pressure for effecting the operation of said valve means, and a safety valve device operating upon failure of the first valve device to act for effecting the operation of said valve means.
25. The combination with a brake pipe, of a 50 valve mechanism for making a first and then a second reduction in brake pipe pressure comprising valve means for initiating the second reduction in brake pipe pressure, a valve device operating upon completion of the first reduction in brake pipe pressure for effecting the operation of said valve means, a safety valve device operating upon failure of the first valve device to act for effecting the operation of said valve means, and means for delaying the operation of said 55 safety valve device for a period of time after the first reduction in brake pipe pressure is completed.
26. The combination with a brake pipe and an 60 equalizing discharge valve device for venting fluid from the brake pipe, of means for automatically effecting successive reductions in brake pipe pressure by operation of said discharge valve device including valve means for initiating the second reduction in brake pipe pressure, a valve device subject to the pressure of fluid vented from the brake pipe by operation of said discharge valve device for effecting the operation of said valve means upon completion of the first reduction in brake pipe pressure, and a safety valve device subject to the pressure of fluid vented from 65 the brake pipe in making the first reduction in brake pipe pressure and operating in case the first valve device fails to act to effect the operation of said valve means.
27. The combination with a brake pipe, equalizing reservoir, and an equalizing discharge valve device subject to the opposing pressures of the brake pipe and the equalizing reservoir, of a reduction reservoir, valve means for connecting said reduction reservoir to said equalizing reservoir, 10 a valve for controlling said valve means, a movable abutment subject to the pressure of fluid vented from the brake pipe by operation of said discharge valve mechanism for operating said valve, a second valve for controlling said valve means, and a movable abutment subject to the pressure of fluid vented from the brake pipe for operating said second valve.
28. The combination with a brake pipe, equalizing reservoir, and an equalizing discharge valve 15 device subject to the opposing pressures of the brake pipe and the equalizing reservoir, of a reduction reservoir, valve means for connecting said reduction reservoir to said equalizing reservoir, a valve for controlling said valve means, a movable abutment subject to the pressure of fluid vented from the brake pipe by operation of said discharge valve mechanism for operating said valve, a second valve for controlling said valve means, a reservoir adapted to be charged with 20 fluid vented from the brake pipe, and a movable abutment subject to the pressure in said reservoir for operating said second valve.
29. The combination with a brake pipe, equalizing reservoir, and an equalizing discharge valve 25 device subject to the opposing pressures of the brake pipe and the equalizing reservoir, of a reduction reservoir, valve means for connecting said reduction reservoir to said equalizing reservoir, a valve for controlling said valve means, a movable abutment subject to the pressure of fluid vented from the brake pipe by operation of said discharge valve mechanism for operating said valve, a second valve for controlling said valve means, a reservoir adapted to be charged with 30 fluid vented from the brake pipe, and a movable abutment subject to the pressure in said reservoir for operating said second valve.
30. The combination with a brake pipe, equalizing reservoir, and an equalizing discharge valve 35 device subject to the opposing pressures of the brake pipe and the equalizing reservoir, of a reduction reservoir, valve means for connecting said reduction reservoir to said equalizing reservoir, a valve for controlling said valve means, a movable abutment subject to the pressure of fluid vented from the brake pipe by operation of said discharge valve mechanism for operating said valve, a second valve for controlling said valve means, a reservoir adapted to be charged with 40 fluid vented from the brake pipe, a movable abutment subject to the pressure in said reservoir for operating said second valve, and a check valve 45 for preventing back flow from said reservoir.
31. In an automatic train control apparatus, 50 the combination with an application pipe, a reduction in pressure in which is adapted to effect an application of the brakes, a slow acting valve device for venting fluid from said application pipe, a speed controlled blow down valve, a valve for connecting said slow acting valve device with said blow down valve, a piston for operating said valve, and a magnet controlled valve for controlling the operation of said piston.

32. In an automatic train control apparatus, the combination with an application pipe, a reduction in pressure in which is adapted to effect an application of the brakes, a slow acting valve device for venting fluid from said application pipe, a speed controlled blow down valve, a speed governor controlled valve, a valve for connecting the application pipe to said speed governor controlled valve, a piston for operating said valve, a second slow acting valve device for controlling the operation of said piston, a magnet controlled valve, and a valve for connecting the first slow acting valve device with said blow down valve and the second slow acting valve device with said magnet controlled valve.

33. In an automatic train control apparatus, the combination with an application pipe, a reduction in pressure in which is adapted to effect an application of the brakes, a slow acting valve device for venting fluid from said application pipe, a speed controlled blow down valve, a speed governor controlled valve, a valve for connecting the application pipe to said speed governor controlled valve, a piston for operating said valve, a second slow acting valve device for controlling the operation of said piston, a magnet controlled valve, a valve for connecting the first slow acting valve device with said blow down valve and the second slow acting valve device with said magnet controlled valve, a piston for operating said connecting valve, and a magnet controlled valve for controlling the operation of said piston.

34. In an automatic train control apparatus, the combination with a pipe and means operated upon a reduction in pressure in said pipe for effecting an application of the brakes, of a stop reservoir, means operated upon a change in the signal indication for connecting said stop reservoir to said pipe, and means under the control of the engineer for controlling communication through which said reservoir is connected to said pipe.

35. In an automatic train control apparatus, the combination with a pipe and means operated upon a reduction in pressure in said pipe for effecting an application of the brakes, of a stop reservoir, means for connecting said reservoir to the atmosphere and operated upon a change in the signal indication for connecting said stop reservoir to said pipe, and means under the control of the engineer for controlling communication through which said reservoir is connected to said pipe.

36. In an automatic train control apparatus, the combination with a pipe and means operated upon a reduction in pressure in said pipe for effecting an application of the brakes, of a stop reservoir, means for connecting said reservoir to the atmosphere and operated upon a change in the signal indication for connecting said stop reservoir to said pipe, and means operable by the engineer for closing communication through which said reservoir is connected to said pipe.

37. In an automatic train control apparatus, the combination with a pipe and means operated upon a reduction in pressure in said pipe for effecting an application of the brakes, of a stop reservoir, means for connecting said reservoir to the atmosphere and operated upon a change in the signal indication for connecting said reservoir to said pipe to thereby effect a reduction in pressure in said pipe and a consequent application of the brakes, and means operable by the engineer for closing communication through which

said reservoir is connected to said pipe to thereby prevent an application of the brakes.

38. In an automatic train control apparatus, the combination with a pipe and means operated upon a reduction in pressure in said pipe for effecting an application of the brakes, of a stop reservoir, means for connecting said reservoir to the atmosphere and operated upon a change in the signal indication for connecting said reservoir to said pipe to thereby effect a reduction in pressure in said pipe and a consequent application of the brakes, and means operable by the engineer for closing communication through which said reservoir is connected to said pipe and for opening communication for supplying fluid under pressure to said reservoir.

39. In an automatic train control apparatus, the combination with a pipe and means operated upon a reduction in pressure in said pipe for effecting an application of the brakes, of a stop reservoir, means for connecting said reservoir to the atmosphere and operated upon a change in the signal indication for connecting said reservoir to said pipe, to thereby effect a reduction in pressure in said pipe, a valve device for controlling communication through which said reservoir is connected to said pipe, and manually operated means for operating said valve device to close said communication.

40. In an automatic train control apparatus, the combination with a pipe and means operated upon a reduction in pressure in said pipe for effecting an application of the brakes, of a stop reservoir, means for connecting said reservoir to the atmosphere and operated upon a change in the signal indication for connecting said reservoir to said pipe, to thereby effect a reduction in pressure in said pipe, a valve device operated by an increase in fluid pressure for closing communication through which said reservoir is connected to said pipe, and manually operated means for supplying fluid to said valve device.

41. In an automatic train control apparatus, the combination with a pipe and means operated upon a reduction in pressure in said pipe for effecting an application of the brakes, of a stop reservoir, means for connecting said reservoir to the atmosphere and operated upon a change in the signal indication for connecting said reservoir to said pipe, to thereby effect a reduction in pressure in said pipe, a valve device operated by an increase in fluid pressure for closing communication through which said reservoir is connected to said pipe, a normally charged reservoir, a manually operated valve for connecting said reservoir to said valve device, and a restricted blow down port for gradually venting the fluid pressure from said valve device.

42. In an automatic train control equipment, the combination with a brake pipe, of means operated upon a change in the signal indication for effecting an application of the brakes, manually controlled means for effecting a reduction in brake pipe pressure, and means for suppressing the operation of said signal indication controlled means so long as the brake pipe pressure is being reduced.

43. In an automatic train control equipment, the combination with a brake pipe, of means operated upon a change in the signal indication for effecting an application of the brakes, manually controlled means for suppressing the operation of said signal indication controlled means, and means operated upon a predetermined reduction

in brake pipe pressure for maintaining said suppressing means in its suppressing position.

44. In an automatic train control equipment, the combination with a brake pipe, of means operated upon a change in the signal indication for effecting an application of the brakes, manually controlled means for effecting a reduction in brake pipe pressure, means operated by fluid vented from the brake pipe for suppressing the operation of said signal indication controlled means, and means operated upon a predetermined reduction in brake pipe pressure for maintaining said suppressing means in its suppressing position.

45. In an automatic train control equipment, the combination with a brake pipe, of means operated upon a change in the signal indication for effecting an application of the brakes, manually controlled means for effecting a reduction in brake pipe pressure, means operated by fluid vented from the brake pipe for suppressing the operation of said signal indication controlled means, and means operated upon a predetermined reduction in brake pipe pressure for supplying fluid from the brake pipe to said suppressing means to maintain said suppressing means in its suppressing position.

46. In an automatic train control apparatus, the combination with a brake pipe, of means for automatically effecting a reduction in brake pipe pressure in two stages, mechanism for cutting said means into and out of operation, and means for effecting the movement of said mechanism to its cut-in position when the speed of the train is less than a predetermined degree.

47. In an automatic train control apparatus, the combination with a brake pipe, of means for automatically effecting a continuous reduction in brake pipe pressure when the speed of the train exceeds a predetermined speed limit and for automatically effecting a two stage reduction in brake pipe pressure when the speed of the train is less than said predetermined speed limit.

48. In an automatic train control apparatus, the combination with a brake pipe, of means for automatically effecting a continuous reduction in brake pipe pressure or a gradual reduction in brake pipe pressure, and means governed by the speed of the train for causing one or the other of said reductions to be effected.

49. In an automatic train control apparatus, the

combination with a brake pipe, of means for automatically effecting a continuous reduction in brake pipe pressure or a gradual reduction in brake pipe pressure, means for causing one or the other of said reductions to be effected, and means controlled by the speed of the train for selectively effecting one or the other of said reductions.

50. In an automatic train control apparatus, the combination with a brake pipe, of means for automatically effecting a continuous reduction in brake pipe pressure or a gradual reduction in brake pipe pressure, a speed controlled governor, and a valve device operated by said governor for causing one or the other of said reductions to be effected.

51. In an automatic train control equipment, the combination with automatic apparatus operable to effect an application of the brakes, of a brake pipe, manually operable means for reducing the brake pipe pressure to effect an application of the brakes, and valve means operated by fluid vented from the brake pipe by operation of said manually operable means for preventing the operation of said automatic apparatus, communication through which fluid vented from the brake pipe is supplied to said valve means being controlled by said automatic apparatus.

52. In an automatic train control equipment, the combination with automatic apparatus operable to effect an application of the brakes, of a brake pipe, manually operable means for reducing the brake pipe pressure to effect an application of the brakes, and valve means operated by fluid vented from the brake pipe by operation of said manually operable means for preventing the operation of said automatic apparatus, communication through which fluid vented from the brake pipe is supplied to said valve means being closed when the automatic apparatus operates to effect an application of the brakes.

53. In an automatic train control apparatus, the combination with a brake pipe, of means for automatically effecting a reduction in brake pipe pressure in two stages, a speed governor operated at a speed proportional to the speed of the train, and means operated by said speed governor when the speed of the train exceeds a predetermined speed limit for preventing the brake pipe pressure from being reduced in two stages.

CLYDE C. FARMER.
